Metal Products Corporation, Brooklyn, N.Y.

Filed Oct. 21, 1964, Ser. No. 82,273

Term of patent 14 years

(Cl. D44—6)

FIG.1

FIG.2

FIG. 3

FIG. 4

FIG. 5

FIG. 6

FIG. 1 is a perspective view of a bread box showing my new design;

FIG. 2 is a front view thereof;

FIG. 3 is a rear view thereof;

FIG. 4 is a top view thereof;

FIG. 5 is an elevational view of the right side thereof; and

FIG. 6 is an enlarged sectional view taken along line 6-6 of FIG. 2.

The characteristic feature of my design resides in the combination on a bread box of the configuration shown of the recessed margin framing the door and the elongated handle of the configuration disclosed substantially one-third the width of the door adjacent the top of the door.

I claim:

The ornamental design for a bread box, substantially as shown and described.
